US00D870142S

(12) **United States Design Patent** (10) **Patent No.:** **US D870,142 S**
Dailey et al. (45) **Date of Patent:** **** Dec. 17, 2019**

(54) **DIGITAL PATHOLOGY APPARATUS
DISPLAY SCREEN WITH GRAPHICAL USER
INTERFACE**

(71) Applicant: **Leica Biosystems Imaging, Inc.**, Vista, CA (US)

(72) Inventors: **Timothy Dailey**, San Diego, CA (US); **Nicholas Newberg**, San Marcos, CA (US); **Peyman Najmabadi**, San Diego, CA (US); **Lance Mikus**, San Marcos, CA (US); **Prentash Djelosevic**, Oceanside, CA (US)

(73) Assignee: **LEICA BIOSYSTEMS IMAGING, INC.**, Vista, CA (US)

(**) Term: **15 Years**

(21) Appl. No.: **29/631,501**

(22) Filed: **Dec. 29, 2017**

(51) LOC (12) Cl. **14-04**

(52) U.S. Cl.

USPC **D14/488**

CLAIM

The ornamental design for a digital pathology apparatus display screen with graphical user interface, as shown and described.

DESCRIPTION

The FIGURE is a front view of a digital pathology apparatus display screen with graphical user interface according to the present invention.

The broken line showing of a digital pathology apparatus display screen with graphical user interface is included for the purpose of showing portions of the article which form no part of the claim.

1 Claim, 1 Drawing Sheet
